UNITED STATES PATENT OFFICE.

JOHN A. DEWIRE, OF CHICAGO, ILLINOIS, ASSIGNOR, BY MESNE ASSIGNMENTS, TO THE KINGSLEY-MILLER COMPANY, OF CHICAGO, ILLINOIS, A CORPORATION OF ILLINOIS.

RADIATOR CAP.

Application filed October 2, 1924. Serial No. 741,107.

This invention relates to radiator caps, and with regard to certain more specific features, to radiator caps of the so-called keyless locking type.

5 Among the several objects of the invention may be noted, the provision of a simple and inexpensive radiator cap, of rugged and durable means for preventing unauthorized removal of the cap from the radiator, and of 10 ready means for opening and closing the caps while pouring in radiator contents. Other objects will be in part obvious and in part pointed out hereinafter.

The invention accordingly comprises the 15 features of construction, combination of elements, and arrangements of parts, which are exemplified in the constructions hereinafter described and the scope of the application of which will be indicated in the following claims.

In the accompanying drawing, in which is shown one of various possible embodiments of the invention,

Fig. 1 is a front elevation;

25 Fig. 2 is a side elevation, partly in central section, showing the cap open.

Fig. 3 is a side elevation, partly in central section, showing the cap closed.

Similar reference characters indicate corresponding parts throughout the several 30 views of the drawings.

Referring now more particularly to Fig. 2 of the accompanying drawings, there is illustrated at 1 a main supporting ring having its lower portion 3 internally threaded to engage the upper end of the threaded radiator neck 5. (Fig. 1.) This ring 1 is surrounded by the body of the cap, in the form of a second outer ring 7 locked to the 40 supporting ring 1 by the circular spring ring 9 received in suitable grooves in both the supporting and outer rings. After the cap has been telescoped over the supporting ring the circular spring ring lying in the supporting ring groove is under compression until the grooves line up, when it springs outwardly, overlaps the joint between cap and inner ring, and thereby locks the supporting ring and cap against relative axial movement, while it permits the cap to rotate upon the supporting ring. The cap may have any suitable design and is shown provided with ornamental extensions or arms 11, which

may also serve as convenient handles for rotating it.

55 In order to lock the cap and ring against relative rotation in one direction, while permitting free relative rotation in the opposite direction, there is provided preferably a pair of ball clutches arranged on opposite sides of the ring. Each clutch comprises a steel ball 13 carried loosely within an inclined slot 15 cut tangentially on ring 1. The slot being tangentially cut is of varying depths, being deepest at the middle portion and shallow at the ends thereby affording wedging action on the balls 13 at the slot extremities. When the cap is rotated in a direction such as to screw the ring 1 down over the neck 5, the balls 13 being normally retained by 70 gravity at the lower ends of the inclined slots are wedged in at the lower ends of said slots, thereby locking the cap to the supporting ring, whereupon the lower threaded portion 13 of the supporting ring 75 is screwed home. Rotating the cap 7 to unscrew the device from a radiator results in the balls being rolled up (by frictional engagement with the cap body) in their respective inclined slots to the deep central 80 portions of the same where said balls lose their grip and the cap turns on the supporting ring without unscrewing it. The bridge 17 over the central part of the slot 15 breaks contact between the balls and the 85 adjacent surface on the cap thereby preventing a frictional bore from carrying the balls on up to a jamming position at the upper end of the slots with consequent turning off of the device. The lower skirt 19 of the cap 90 covers the lower portion of the supporting ring thereby preventing the use of a Stillson or other wrench for loosening the ring.

95 In order to ensure tight engagement of the ball clutch during application of the device to a radiator neck vertical slots are cut in the internal surface of the caps. During application of a cap to a radiator, the balls reach the vertical slots simultaneously and imbed themselves to a substantial extent in 100 the cap, thus ensuring engagement between ring and cap.

If the entire radiator is removed in repairing the same in a garage, for example, the radiator may then be turned upside down, 105 resulting in the reversal of the locking ac-

tion of the ball clutches. That is, in an inverted position of the radiator the balls tend to roll to the opposite ends of the grooves 17, as a result of which the cap may rotate the supporting ring in a direction such as to permit unscrewing of the device from the radiator, but the cap will turn freely when rotated in the opposite direction.

The cap includes a hinged cover 21, the hinge being arranged preferably at the rear. The hinge consists of a pin 23 passing through two lugs on the cap and a single lug on the cover. The hole for the pin does not pass completely through one of the cap lugs, making it difficult or impossible to drive the pin out. Said pin has a driving fit in said cap lugs, rendering it difficult or impossible to withdraw the pin, inasmuch as the exposed end does not project beyond its supporting lug.

The front portion of the cap 7 is enlarged to form a support for the plate 25. The plate 25 may carry any suitable ensignia and be ornamental. It is shown in the form 26 of a shield bearing the initial of the owner. The upper portion of the forwardly enlarged portion of the cap extends rearwardly in the form of two flat walls 27 and a third centrally located catch 29. These 30 walls serve to enclose the latch, to be described. The catch 29 engages with the latch when the latter is manipulated to lock shut the hinged cover.

Forwardly located on the hinged cover 21 is the lug 31 hollowed out to receive the thumb or finger plate 33. Said thumb plate 33 comprises, beside its plate, two lower legs 35 which are pinned within the hollow lug 31 and straddle the latch 37, said latch being pinned in a slot formed from the hollow portion to the forward edge of the lug 31. The latch and thumb plate are rotatably mounted on their respective pins. The latch 37 comprises a flat plate having formed at its lower end an engaging ear 38 which when properly set, engages the catch 29, thereby holding the cover shut. When otherwise set it clears the catch and permits opening of the cover. Above its center of rotation the 50 latch has formed thereon the ear 39, which engages with the lower edge of the thumb plate when the latter is swung forward thereby throwing the engaging ear 38 rearwardly allowing it to disengage the catch 29, in order that the cover may be raised.

The latch also comprises a rearward extension having formed on its upper edge two indentations 41 and 43, the rear indentation 43 being higher than the forward one 41 60 when the latch is in open position, i. e., when the cover is ready to open. Therefore assuming that it is desired to latch the cover shut, the thumb plate is pushed rearwardly engaging first with the forward indentation, thereby throwing the ear 38 upwardly

into engagement with catch 29. The downward reaction holds the cover shut. If in this position the reaction is not great enough to compress the gasket 45 in between the cover and the supporting ring, the thumb plate is pushed further back until it does engage the rearward indentation thereby increasing the downward thrust on the cover until the gasket is enough compressed, and a tight closing of the cover accomplished. 75 When a gasket is new and unworn, engagement in the first indentation is sufficient to compress it. The deep indentation 47 is cut to such a depth as will bring about a proper clearing position for the ear 38, when the 80 bottom of said indentation comes in contact with the lower edge of the thumb plate as it is rotated forward with a view to opening the cover. It also serves to limit the throw of the thumb plate forward so that it will not strike the forwardly enlarged portion of the cap. The thumb plate and latch are pinned in a manner similar to the previously described cover hinge, making their unauthorized removal difficult or impossible. 90

A thin metallic gasket 49 is interposed between the gasket 45 and the inner ring 1 so that turning of the outer body on the inner ring may be accomplished without tearing the gasket. The gasket would otherwise 95 tend to cling to the inner ring as well as the rotating cover were it not prevented by the gasket 49 which provides a free sliding surface.

The device carried upon the cap may be 100 a motometer 51 or other suitable instrument or ornament, and is held to the cap between a shoulder 53 and a nut 55, fitted with set-screw and washer, on its threaded stem 57. The stem carries a second nut 59 bearing 105 against a washer 61 of some soft metal such as annealed brass or copper and having a raised central portion. The washer 61 is of such diameter as to be received loosely within the undercut groove 63 of the cover. In 110 assembling the parts, the nut 59 is tightened until the crowned washer 61 flattens out somewhat and increases its diameter sufficiently to lock it permanently within the groove 63. This washer prevents access to 115 the nut 55, which holds the motometer to the cap, and thus prevents the removal of the motometer from the cap. Accidental or intentional loosening or removal of the nut 59 does not result in loosening the washer 120 61, which cannot be removed except by destroying or otherwise mutilating the washer or some other part of the structure.

In filling the radiator the operator simply pulls forward the thumb plate and swings 125 the cover up. After filling he drops the cover and presses back the thumb plate thereby closing the device tightly and clamping the outer ring to the inner ring through the gasket, thus holding the cap in a given 130

position on the radiator. Two movements suffice for the entire operation.

In view of the above, it will be seen that the several objects of the invention are 5 achieved and other advantageous results attained.

As many changes could be made in carrying out the above constructions without departing from the scope of the invention, it 10 is intended that all matter contained in the above description or shown in the accompanying drawings shall be interpreted as illustrative and not in a limiting sense.

I claim:

- 15 1. In a radiator-cap, the combination of a cap-body adapted to be secured to a radiator-neck and having a catch, a cover hinged on said cap-body, a compressible gasket between said cover and cap-body, a latch 20 hinged on said cover adapted to engage said catch to clamp said cover closed on said gasket, and a finger-piece hinged on said cover cooperating with said latch and adapted to release it from said catch and adapted 25 to cause it to clamp said cover closed on said gasket by engagement with said catch.
2. In a radiator-cap, the combination of a cap-body adapted to be secured to a radiator-neck and having a catch, a cover 30 hinged on said cap-body, a compressible gas-

ket between said cover and cap-body, a latch hinged on said cover adapted to engage said catch to clamp said cover closed on said gasket and having graduated surfaces, and a finger-piece hinged on said cover cooperating with said latch adapted to release it from said catch and adapted to cause said latch to clamp said cover closed on said gasket in different degrees by engagement with said graduated surfaces. 35

3. In a radiator-cap, the combination of a cap-body adapted to be secured to a radiator-neck and having a catch, a cover hinged on said cap-body, a compressible gasket between said cover and cap-body, a 40 latch hinged on said cover adapted to engage said catch to clamp said cover closed on said gasket and having an ear and graduated surfaces, and a finger-piece hinged on said cover cooperating with said latch adapted 45 to release it from said catch by rocking said latch by engagement with its ear and adapted to cause said latch to clamp said cover closed on said gasket in different degrees by engagement with said graduated 50 surfaces. 55

In testimony whereof, I have signed my name to this specification this 29th day of September, 1924.

JOHN A. DEWIRE.
